[57] CLAIM

The ornamental design for an electric face cleaner, as shown and described.

DESCRIPTION

FIG. 1 is a perspective view showing the top, front and right side of our new design for an electric face cleaner;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front elevational view similar to FIG. 2 but with the cap removed for a complete disclosure of the underlying parts;

FIG. 9 is a rear elevational view thereof;

FIG. 10 is a right side elevational view thereof;

FIG. 11 is a left side elevational view thereof;

FIG. 12 is a top plan view thereof; and,

FIG. 13 is a bottom view of the cap shown separately for clarity of disclosure.
